CLAIM

The ornamental design for a combined container and lid, as shown and described.

DESCRIPTION

FIG. 1 is a perspective view of a combined container and lid showing our new design;

FIG. 2 is a front elevational view thereof;

FIG. 3 is a top plan view thereof;

FIG. 4 is a right side elevational view thereof;

FIG. 5 is a bottom plan view thereof;

FIG. 6 is a left side elevational view thereof;

FIG. 7 is a cross-sectional view thereof taken along line 7-7 in FIG. 5;

FIG. 8 is another perspective view thereof, with the tab in lifted condition; and,

FIG. 9 is another perspective view thereof, with the tab removed in an alternate configuration.

The broken line portions are included to show unclaimed subject matter only and form no part of the claimed design.
